MEANS AND METHOD FOR ASSEMBLING
THE INDIVIDUAL SPRINGS OF SPRING
UNITSGeorge E. Taylor, Chicago, Ill., assignor to Samuel
E. Sosna and George E. Taylor, as trustees

Application January 23, 1939, Serial No. 252,468

16 Claims. (Cl. 140—3)

This invention relates to a means and method for assembling and securing together the individual springs of spring units such as are employed in innerspring mattresses, cushions for 5 chairs and settees, and in like articles.

The individual springs in spring units of the above described type are arranged in the units in transversely and longitudinally extending rows and portions of the peripheries of the springs in 10 either the transversely or the longitudinally extending rows overlap, and in some instances there is such overlapping in both directions. Heretofore the overlapped portions of the springs have been secured together by means of a helical retainer which was threaded along between adjacent rows and passed about the overlapping portions 15 of the springs in such adjacent rows, such retainers usually being of a length sufficient to extend from end to end or side to side of the 20 spring unit, as the case might be, and the ends of such retainers sometimes have been fastened to similar retainers extended along the edges of the units.

The helical retainers are cut to length prior 25 to being installed in the spring units and are rotated into retaining position so as to thereby be threaded about the various springs to be secured thereby. Heretofore power driven means have been provided for imparting rotative movement 30 to the helical retainers but such power driven means have been manually controlled. Considerable skill is entailed in operating such power driven means in an amount to cause the helical retainer to be advanced to the point where the 35 leading end thereof can be conveniently passed about the overlapping portions of springs to be retained thereby.

It is important that the springs in the longitudinally and transversely extending rows be retained 40 in alignment for otherwise the unit does not function satisfactorily in the use to which it is put. In order to accomplish such alignment the various springs have been arranged on pins or pegs that in turn have been arranged in longitudinally and 45 transversely extending rows and the spacing of the pegs has been that desired for the spring units. With the springs so positioned all that is required is to secure the springs by means of the retainers without altering the position thereof on 50 the pins or pegs.

However, the operators of the power driven retainer advancing means would sometimes so operate such means that the leading end of the helical retainer would not be advanced far enough 55 to be in proper position to be passed about the

overlapping portions of the springs to be retained thereby, and in other instances the power driven means would be so operated that the leading end thereof would be advanced beyond the point whereat it was to be passed about the overlapping portions of springs in adjacent rows. In those instances where the leading end of the helical retainer was not advanced far enough to be in position to be passed about the overlapping portions of the adjacent springs, or where such 10 leading end was advanced beyond such overlapping portions, the operators have distorted the springs so that the helical retainer could be passed thereabout with the result that the springs were displaced and when a unit was completed certain of the springs would be in a cocked or otherwise improper position. This detracts from the 15 commercial value of the finished unit and renders it otherwise unsatisfactory.

Moreover, the leading ends of the above referred to helical retainers are rather sharply pointed and where manually controlled power driven means were employed to advance such retainers and the retainers were stopped in indiscriminate positions, the sharply pointed end of 20 the retainer was often in such a position that it was necessary for the operator to grab the pointed end in order to properly pass it around the overlapping portions of springs to be retained thereby, or, in some instances, because of 25 improper location of the leading end of the spring retainer, the operator would inadvertently grab the pointed end. This often resulted in more or less serious injuries to the operators of the 30 manually controlled power driven helical retainer 35 advancing means such as have been employed heretofore.

It will be apparent from the foregoing that considerable skill and dexterity was required to properly operate the manually controlled power 40 driven means heretofore employed for the purpose of advancing helical retainers such as are employed to interconnect the adjacent springs in spring units of the above described type, and such skill and dexterity could only be acquired 45 by a prolonged apprenticeship which was not profitable to the operator and which was expensive to the employer of the operator.

In view of the foregoing and other kindred difficulties which have been encountered in assembling spring units, the primary object of my invention is to accurately advance helical retainers such as are employed for interconnecting adjacent springs in spring units in an amount determined by the spacing of the overlapping por- 55

tions of one set of adjacent springs from the overlapping portions of an adjacent set of adjacent springs.

An object ancillary to the foregoing is to accurately interrupt advancing movement of a helical retainer after a predetermined amount of advancing thereof.

It will be understood that different sizes of springs are employed in different spring units and that even where correspondingly sized springs are employed the spacing between the various rows of springs in different units may vary and in view of this it is desirable that whatever means are employed for effecting advancing movement of a helical retainer in a predetermined amount be so constructed and arranged that advancing movement of varying magnitudes may be imparted to helical retainers used in spring assemblies and so to do is still another object of the present invention.

Other and further objects are to rotate a helical spring retainer a predetermined number of turns to thereby insure a predetermined degree of advancing movement thereof; to automatically interrupt operation of power operated means for advancing a spring retainer and thereby insure uniform operation of the power operated means in various operations thereof; to accurately and positively interrupt operation of power operated means for advancing a helical spring retainer; and to maintain such power operated means in operation for a predetermined period each time it is set in operation.

Still further objects are to so support a power operated means for advancing a helical spring retainer that the power operated means itself will be advanced in the course of advancing of the helical spring retainer; to effectively dissipate momentum accruing in the course of operation of a power operated helical retainer advancing means; to bring such means to rest in an identical position at the end of various operations thereof; and to provide a novel helical spring retainer advancing means of simple and economical construction and efficient and positive operation.

Other and further objects will be apparent from the following description wherein reference is made to the accompanying drawings in which—

Fig. 1 is a top plan view of my novel spring retainer advancing means and in which a portion of the track along which such means travel in the course of operation thereof is broken away;

Figs. 2 and 3 are sectional detail views taken respectively and substantially on the lines 2—2 and 3—3 on Fig. 1;

Fig. 4 is a side elevation of the apparatus illustrated in Fig. 1;

Figs. 5 and 6 are sectional detail views taken respectively and substantially on the lines 5—5 and 6—6 on Fig. 1;

Fig. 7 is a fragmentary sectional view of a connector employed in the apparatus;

Fig. 8 is a top plan view showing the manner in which my novel spring retainer advancing means is put to use;

Fig. 10 is a view taken substantially on the line 10—10 on Fig. 8 and drawn to an enlarged scale;

Fig. 11 is a top plan view drawn to an enlarged scale and illustrating the position in which the leading end of a helical spring retainer comes

to rest at the end of each advancing movement imparted thereto by my novel apparatus; and

Fig. 12 is a wiring diagram.

The preferred form of my novel spring retainer advancing means shown in the accompanying drawings includes a bed plate 15 having brackets 16 and 17 fast thereto at opposite ends thereof and extending upwardly therefrom. A substantially U-shaped bracket 18 is secured to the upper end of the bracket 16 and a grooved roller 19 is rotatably mounted between the limbs of the bracket 18 adjacent the free upper ends of such limbs. Another substantially U-shaped bracket 20 is secured to the upper end of the bracket 17 and a grooved roller 21 is rotatably mounted between the limbs of the bracket 20 adjacent the free upper ends of such limbs. An elongated substantially T-shaped track 22 is provided which is suitably supported in a manner not shown from the ceiling or other support with the free end of the stem portion thereof extended upwardly, and the bed plate 15 is supported from the track 22 through the brackets 16, 18, 17 and 20 by having the track pass between the limbs of the brackets 18 and 20 so that the grooved rollers 19 and 21 may have the stem portion of the T-shaped section of the track extended thereinto. Thus the sides of the grooves in the rollers 19 and 21 embrace the sides of the stem of the T-shaped track 22 and tend to prevent sidewise swaying of the bed plate 15 which is nevertheless supported for free movement along the track 22.

A block 23 is mounted on the top side of the bed plate 15 adjacent to the bracket 16 and a motor 24 is fast to the upper side of this block. A worm gear 25, Fig. 3, is mounted on one end of the shaft of the motor 24 and meshes with a worm wheel 26, Fig. 4, that is fast to the shaft 27 which is journaled in bearings provided in the gear box 28, Fig. 1, carried by the frame of the motor 24 and the bearing 29 supported from the bed plate 15 by the bracket 30. A connector 31 is mounted on the free end of the shaft 27 that is positioned adjacent the bracket 16, this connector being tubular in configuration and having a helical groove 32, Figs. 1 and 7, on the interior thereof leading from the free end thereof and one end of a helical spring retainer R is adapted to be threaded into the helical groove 32.

With one end a retainer R secured in the connector 31 it is manifest that if the motor 24 is set in operation, the retainer R will be rotated, and the direction of rotation of the motor 24 and the geared connection between this motor and the shaft 27 is such that the shaft 27 will be rotated in such a direction that the retainer R will be rotated in the direction of the lead of the helix thereof. Thus, as best shown in Fig. 12, a terminal 33 in the switch S is connected to a line 34 wire 34 leading from a source of current by a conductor 35. The other terminal 36 of the switch S is connected by conductors 37 and 38 to one terminal of the motor 24, the other terminal of the motor 24 being connected to the line 39 wire 39 that also leads to a source of current. Thus, when the bridging contact 40 of the switch S closes circuit between the terminals 33 and 36, the motor 24 is set in operation and thereupon an advancing movement is imparted to the retainer R.

It has been explained heretofore that it is essential that a spring retainer such as the retainer R be advanced only in a predetermined amount in order that the various springs to be

secured together to afford a spring unit will be properly secured together and to further explain this reference is made to Fig. 8 wherein it will be seen that two strips 41 and 42 are provided which have a plurality of pegs or pins 43 provided thereon at regularly spaced intervals that are adapted to receive springs 44 which are to be secured together to afford a spring unit such as that which can be used in an innerspring mattress or in the cushion or back of upholstered furniture or in other kindred articles of furniture or the like.

When a plurality of springs as 44 are to be connected together to provide a spring unit, the size of the spring is first determined and then spacing between the various rows of such springs is determined and the pins 43 are then secured in the strips as 41 and 42 to give the desired spacing in one direction of the unit. The spacing between the springs in the other direction of the unit is determined by the diameter of the springs themselves, and the strips as 41 and 42 in which the pins as 43 are secured are secured to a table top T or the like such a distance apart that when springs as 44 are mounted on the pins 43 the springs on correspondingly positioned pins 43 on the strips 41 and 42 will slightly overlap as, for example, in the manner illustrated in Fig. 8.

When a plurality of springs are to be assembled into a unit, first springs as 44 are mounted on the pins 43 on the strip 41 and then the table T or the track 22, or both, are adjusted relative to each other so that when a spring retainer R is advanced by rotation of the shaft 27 in the manner above described it will thread over the peripheries of the upper coils of the springs on the pins 43 on the strip 41 that extend toward the strip 42 and the result of this operation is the securing together along one edge of such springs 44 by a spring retainer as Ra.

Thereafter the springs which have been mounted on the pins 43 on the strip 41 which are now interconnected by the spring retainer Ra are moved over onto the pins 43 on the strip 42 and other springs are mounted on the pins 43 on the strip 41. These last named springs when installed on the pins 43 on the strip 41 will overlap portions of the springs 44 that are now mounted on the pins 43 on the strip 42. After the springs have been so arranged, the shaft 27 is again set in operation and the spring retainer Rb is run into position. For convenience the springs mounted on the first of the pins 43 on the strips 41 and 42 will be referred to as being in row A while the springs on the next inwardly of the pins will be referred to as being in the row B and the springs on the next inwardly of the pins 43 will be referred to as being in the row C.

Heretofore when a power operated means was provided for advancing a spring retainer it was solely under control of a manually operated switch such as the switch S and it was necessary for the operator to hold the switch closed and then by judgment cause the switch to open so as to stop the free end of the spring retainer in the position shown in Fig. 11 where the free end of the spring retainer Rc is shown in position to be passed about the overlapping portions of the springs 44a and 44b. Of course when the spring retainer Rc is first advanced it will be necessary to stop it accurately with respect to the overlapping portions of the springs 44c and 44d. In the next operation it will be necessary to stop the leading end of the spring retainer with respect to the overlapping portions of the springs

44a and 44b. Now the distance between the overlapping portions of the springs 44c and 44d in the row A and the overlapping portions of the springs 44a and 44b in the row B is the same as the distance between the overlapping portions of the springs 44a and 44b in the row B and the overlapping portions of the springs 44e and 44f in the row C. Thus when the retainer R is advanced from the overlapping portions of the springs in the row A to the overlapping portions of the 10 springs in the row B and thereafter advanced from the overlapping portions of the springs in the row B to the overlapping portions of the springs in the row C, identical advancing movement should be imparted in both instances. It 15 will be manifest, however, that if the switch S is held closed for too long a time or too short a time uniform advancing movement will not be imparted to a retainer as R. It will either be necessary in such an instance to attempt to 20 slightly advance the retainer R if it has not been advanced far enough or else it will be necessary to manually thread the retainer RR rearwardly in order to back it up and one or the other of these two operations should be performed. However, it has been found that often in such instances an operator will deflect the springs so as to bring overlapping portions thereof into position to be engaged by the leading end of the retainer R, and wherever the retainer R engages 30 springs so flexed it secures the springs so as a result the flexed springs are secured in an improper position in so far as the unit as a whole is concerned.

Moreover, if the operator does not stop the 35 retainer R substantially in the position shown in Fig. 11 it will frequently be necessary for the operator to grasp the free end of the retainer with the result, as explained above, that often the operator's hands are cut. However, if the retainer R is always stopped substantially in the position shown in Fig. 11, it may be grasped inwardly from the end and passed about the overlapping portions of adjacent springs, and when the retainer is grasped inwardly from the end 45 the likelihood of the operator's hands being cut is substantially reduced if not entirely eliminated.

Thus, in accordance with my invention I arrange the power operated spring retainer advancing means in such a way that once it is set in 50 operation it will advance a spring retainer as R in a predetermined amount, and then when it has advanced the spring retainer in this predetermined amount will interrupt movement in a predetermined position so that the leading end 55 of the retainer will be in a position substantially like that shown in Fig. 11 which will enable the operator to expeditiously pass the leading end of the retainer about the overlapping portions of the adjacent springs to thereafter set the device 60 in operation so that the retainer will then be threaded about the overlapped portions of adjacent springs and pass on to the next overlapping portions of adjacent springs.

In order to insure that the foregoing will be 65 accomplished I provide a worm gear 45 on the shaft 27 that meshes with a worm wheel 46 fast on the shaft 47 journaled in plates 48 and 49. Fig. 3, fast to the top of the bed plate 15. In view of the geared connection between the shafts 27 and 47 it is manifest that the shaft 47 will be set in rotation each time the shaft 27 is set in rotation. Thus, means are provided on the shaft 47 for maintaining the circuit to the motor 24 closed once this circuit has been closed and the 75

motor and therefore the shaft 47 set in operation.

To accomplish the foregoing, a disc cam 51 is fast on the shaft 47 and this cam has a notch 52 in the periphery thereof. When the shaft 47 and therefore the motor 24 are at rest the rider 53 on the spring contact 54 that is fast to the top of the plate 15 seats in the notch 52. When, however, the shaft 47 is set in rotation, the notch 52 moves out of alignment with the rider 53 whereupon the spring contact 54 is cammed downwardly and the contact point 55 thereof engages the contact point 56 on the contact strip 57 and circuit is closed from the line wire 34 through conductor 58, contact strip 57, contact point 56, contact point 55, spring contact 54 and conductor 59 to conductor 38 and thence through the motor 24 and conductor 38 to the source of current. Preferably the ratio between the worm gear 45 and the worm wheel 46 is such that the shaft 27 will make a predetermined number of revolutions to a single revolution of the shaft 47 and in the present instance the ratio is preferably such that the shaft 27 makes twelve revolutions to one of the shaft 47. Thus, once the shaft 27 is set in operation and the rider 53 is out of alignment with the notch 52, the shaft 47 will continue in rotation until the rider 53 again seats in the notch 52 but when this occurs the contact point 55 will separate from the contact point 56 and therefore circuit to the motor 24 will be interrupted and power will no longer be supplied to the shafts 27 and 47 from the motor.

However, it is desirable that the shaft 27 be operated at a relatively high rate of speed so that the retainer R will be rapidly advanced from the overlapping portions of adjacent springs in one row as A into association with the overlapping portions of adjacent springs in another row as B. In view of such rapid operation, appreciable momentum will accrue in the various rotating parts and it is therefore desirable that at the time circuit is broken to the motor 24 to brake the rotating parts and thereby dissipate the momentum thereof so that the parts will come to rest in an accurate position. To this end a wheel or drum 60 is fast on the shaft 47 and arcuate brake bands 61 and 62 are disposed about the periphery of this drum. The brake bands 61 and 62 have liners 63 and 64 of suitable friction material provided on the faces thereof disposed toward the periphery of the wheel 60. The block 28 is recessed as indicated at 65, Fig. 2, to receive the ears 66 and 67 respectively provided at adjacent ends of the brake bands 61 and 62, a suitable bolt 68 being passed through openings in these ears with a spring 69 disposed thereabout and between the ears 66 and 67, said spring serving to urge the ears away from each other to thereby urge the liners 63 and 64 away from the periphery of the drum 60. A bracket 70 is fast to the upper side of the bed plate 15 and includes a foot portion 71 on which an ear 72 at the end of the brake band 61 opposite the ear 66 rests. An ear 73 is provided on the corresponding end of the brake band 62 and a bolt 74 is freely passed through openings in the ears 72 and 73 and is threaded into the foot portion 71. A spring 75 is disposed about the bolt 74 between the ears 72 and 73 and serves to urge the ears apart and therefore the liners 63 and 64 away from the periphery of the drum 60.

A bracket 76, Figs. 4 and 9, is fast in the upper surface of the bed plate 15 and a rocker 77 is pivotally mounted thereon as indicated at 78. A notch 79 is provided adjacent one end of the

rocker 77 and receives the head of the bolt 74. An adjusting screw 80 is mounted near the other end of the rocker 77 and bears on one end of a lever 81, Figs. 4 and 6, fulcrumed at 82 on a bracket 83 carried by the bed plate 15. A cam 84 is fast on the shaft 47 and has a lobe 85 thereon. The cam 84 and the disc cam 51 are so fast on the shaft 47 that the notch 52 in the disc cam 51 is aligned with the lobe 85 on the cam 84. Hence when the rider 53 passes into the notch 52 the lobe 85 rides into engagement with the lever 81 and pivots this lever upwardly and the upward movement of the lever 81 is transmitted through the adjusting screw 80 to the rocker 77 whereupon the end of the rocker adjacent which the notch 79 is provided is forced downwardly and inasmuch as this end of the rocker bears on the ear 73 this ear is forced downwardly with the effect of forcing the liners 63 and 64 onto the periphery of the drum 60 which brakes the shaft 47 and other rotating parts. As best shown in Fig. 6, the lobe 85 is provided with a sharp drop so that very soon after movement is imparted to the shaft 47 at the start of an operation, the lever 81 pivots from its upper and operative position shown in full lines in Fig. 6 into its lower or inoperative position shown in broken lines in Fig. 6 and this enables the springs 69 and 78 to disengage the liners 63 and 64 from the periphery of the drum 60.

While the brake afforded by the drum 60 and the parts that cooperate therewith will tend to bring the parts to rest promptly, such means may not always stop the shaft 47 and other parts in identical positions at the ends of different operations of the device and hence, in order to assure that the parts will come to rest in identical positions at such times, a disc 86, Fig. 4, is fast on the shaft 47 which has a tapered notch 87 in the periphery thereof. A bracket 88 is carried by the bed plate 15 and supports a cylinder 89 at the lower end of which a pin 90 is mounted, said pin having a pointed end adapted to seat in the notch 87. As best shown in Fig. 3, a spring 91 in the cylinder 89 acts on the pin 90 to force it toward the periphery of the disc 86, an adjusting screw 92 being threaded into a tapped portion at the upper end of the cylinder 89 to enable adjustment of the tension of the spring 91. The notch 87 in the disc 86 is aligned with the notch 52 on the cam disc 51 and the lobe 85 on the cam 84 so that at the time circuit is broken to the motor 24 and the liners 63 and 64 are applied to the periphery of the drum 60, the pointed pin 90 seats in the notch 87 and arrests further movement of the shaft 47 and the parts connected thereto. By reason of the taper of the notch 87 in the end of the pin 90, the shaft 47 is always brought to rest in an identical position since these two tapers cooperate with each other to insure such positioning of the shaft and therefore the parts connected therewith.

The ratio between the worm gear 45 and the worm wheel 46 is such that the shaft 27 will make a predetermined number of revolutions each time the switch S is closed and in view of this a retainer as R will be advanced a certain number of turns and therefore a predetermined amount in each such operation. Each operation is brought about by momentarily closing the switch S and as soon as the parts are in motion the switch S is opened and thereafter the circuit established at the contact points 55 and 56 maintains the motor in operation until circuit is 75.

broken by separation of these contact points which is effected when the rider 53 passes into the notch 52. At this time, as explained above, the brake is applied to dissipate the momentum that has accrued in the rotating parts and accompanying this the pin 90 seats in the notch 57 and brings the parts to rest in a predetermined position. This predetermined position and the connection of the retainer R to the connector 31 is such that the leading end of the retainer R comes to rest in a position substantially like that shown in Fig. 11 in which position the free end of the retainer may be conveniently hooked about the overlapping portions of adjacent springs and as soon as this is done a new advancing movement may be imparted to the retainer.

Thus referring to Fig. 8, if the retainer Rc had originally been positioned adjacent the overlapping portions of the springs 44c and 44d and the switch S, Fig. 12, had been closed, the leading end of the retainer Rc would have been advanced into the position shown in Figs. 8 and 11. The operator would thereupon grab the retainer Rc rearwardly of the leading end thereof and pass the free end about the overlapping portions of the springs 44a and 44b and then the switch S would again be closed. In this operation the retainer Rc will advance in the manner indicated by broken lines in Fig. 8, into a position ready to have the leading end thereof passed about the overlapping portions of the springs 44e and 44f. This is accomplished in this instance by causing the shaft 27 to make twelve revolutions to one revolution of the shaft 47 which causes twelve turns of the retainer Rc.

If the spacing between the rows A and B and B and C was different from that shown and the pitch of the helix of the retainer R remained the same, then in order to insure proper advancing of the retainer the ratio between the worm gear 45 and the worm wheel 46 would be varied so as to cause the retainer to advance the proper distance. However, if it is preferred not to replace the worm gear 45 and the worm wheel 46 with other gears of different ratio, then the pitch of the helix of the retainer R may be varied so as to cause the retainer to advance in the amount required by the spacing between the rows A and B and B and C and so on. In such an instance, in order that the end of the retainer could be properly fitted into the connector 31, a connector having a helical thread corresponding to the pitch of the helix of the retainer being used would be substituted for the illustrated connector 31.

It will of course be understood that when the end of a retainer as Rc is positioned adjacent the overlapping portions of springs as 44c and 44d and that thereafter this retainer is advanced into a position adjacent the overlapping portions of the springs 44a and 44b, the threading movement of the retainer past the overlapping portions of the springs 44c and 44d causes the bed plate 15 and the parts carried thereby to advance along the track 22 so that at the time the leading end of the retainer has been passed about the last set of overlapping springs on the strips 41 and 42 the connector 31 will be in such a position that the end of the retainer may be removed therefrom and clamped onto the overlapping portions of the adjacent springs to thereby prevent unwinding of the retainer and consequent detachment thereof from the springs and of course the leading end of the retainer is sim-

ilarly connected to the springs that are adjacent to this end.

My improved method of assembling and securing together the various springs that are to be joined to constitute a spring unit resides in uniformly advancing the retainer for the springs in a uniform amount each time the advancing means is set in operation. This insures that the springs will be properly retained in position and thereby enables even a relatively unskilled operator to produce a fully satisfactory product. Moreover, by reason of the fact of the uniform advancing of the retainer in the various operations of the means effecting advancement thereof and the proper positioning of the leading end of the retainer as a consequence of such uniform advancement in an ascertained amount, the likelihood of injury to the operator is substantially reduced, if not entirely eliminated, for the reason that it is unnecessary for the operator to take hold of the relatively dangerous leading end of the retainer.

It will be apparent from the foregoing description that I have also provided a novel apparatus which will cause uniform advancing of a spring retainer in an ascertained amount in various operations and this is brought about by reason of uniform periods of operation of the apparatus, dissipation of momentum accruing in the apparatus during operation thereof, and the positive stopping of the apparatus in uniform positions at the end of each operation thereof. Furthermore, it will be understood that the device is readily susceptible of providing different ascertained but uniform advancing to a retainer either by varying the pitch of the helical retainer or varying the ratio of operation of controlling and controlled parts of the apparatus.

Thus, while I have illustrated a preferred mechanism for carrying out my invention, it is to be understood that resort might be had to other means and hence while I have illustrated and described a preferred embodiment of my invention it is to be understood that this is capable of variation and modification and I therefore do not wish to be limited to the precise details therein set forth but desire to avail myself of such changes and alterations as fall within the purview of the following claims.

I claim:

1. In an apparatus for advancing a spring retainer past the adjacent portions of a plurality of uniformly spaced apart and aligned sets of springs, means for imparting a rotating advancing movement to the retainer, means for setting the means for imparting the rotating advancing movement in operation, and means for automatically interrupting rotation and advance of the retainer when said retainer has been rotated a predetermined number of times and thereby advanced in an amount equal to the spacing between adjacent sets of springs.

2. In an apparatus for advancing a spring retainer past the adjacent portions of a plurality of uniformly spaced apart and aligned sets of springs, means for imparting a rotating advancing movement to the retainer, means for setting the means for imparting the rotating advancing movement in operation, and means for maintaining the means for imparting the rotating advancing movement to the retainer in operation once said means has been set in operation and until the retainer has been rotated a predetermined number of times and for interrupting operation of said means when the retainer has

been rotated said predetermined number of times to thereby have been advanced in an amount equal to the spacing between adjacent sets of springs.

5. In an apparatus for advancing a spring retainer past the adjacent portions of a plurality of uniformly spaced apart and aligned sets of springs, means for imparting the advancing movement to the retainer, means for automatically interrupting operation of the means for imparting the advancing movement when the retainer has been advanced in an amount equal to the spacing between adjacent sets of springs, and means for automatically braking said advancing means when said retainer has been advanced in said amount.

4. In an apparatus for advancing a spring retainer past the adjacent portions of a plurality of uniformly spaced apart and aligned sets of springs, means for imparting the advancing movement to the retainer, means for automatically interrupting operation of the means for imparting the advancing movement when the retainer has been advanced in an amount equal to the spacing between adjacent sets of springs, means for braking said advancing means, and means for automatically effecting operation of said braking means substantially simultaneously with the interruption of operation of the advancing means.

35. In an apparatus for advancing a spring retainer past the adjacent portions of a plurality of uniformly spaced apart and aligned sets of springs, means for imparting the advancing movement to the retainer, means for setting the means for imparting the advancing movement in operation, means for automatically interrupting the operation of said means for imparting the advancing movement when the retainer has been advanced in an amount equal to the spacing between adjacent sets of springs, means for braking said advancing means, and means for automatically effecting operation of said braking means substantially simultaneously with the interruption of operation of the advancing means.

5. In an apparatus for advancing a spring retainer past the adjacent portions of a plurality of uniformly spaced apart and aligned sets of springs, means for imparting the advancing movement to the retainer, means for setting the means for imparting the advancing movement in operation, means for automatically interrupting the operation of said means for imparting the advancing movement when the retainer has been advanced in an amount equal to the spacing between adjacent sets of springs, and means operative to bring said advancing means to rest in an identical position each time operation thereof is interrupted.

60. In an apparatus for advancing a spring retainer past the adjacent portions of a plurality of uniformly spaced apart and aligned sets of springs, means for imparting the advancing movement to the retainer, means for automatically interrupting operation of the means for imparting the advancing movement when the retainer has been advanced in an amount equal to the spacing between adjacent sets of springs, means for braking said advancing means when said retainer has been advanced in said amount, and means operative to bring said advancing means to rest in an identical position each time operation thereof is interrupted.

75. In an apparatus for advancing a spring retainer past the adjacent portions of a plurality

of uniformly spaced apart and aligned sets of springs, means for imparting the advancing movement to the retainer, means for automatically interrupting operation of the means for imparting the advancing movement when the retainer has been advanced in an amount equal to the spacing between adjacent sets of springs, means for braking said advancing means, means for effecting operation of said braking means substantially simultaneously with the interruption of operation of the advancing means, and means operative to bring said advancing means to rest in an identical position each time operation thereof is interrupted.

9. In an apparatus for advancing a spring retainer past the adjacent portions of a plurality of spaced apart and aligned sets of springs, a rotatable shaft, a connector on said shaft to which one end of a spring retainer may be secured, a motor for driving said shaft, a cam shaft, means for rotating the cam shaft from the rotatable shaft in predetermined relation with the rotatable shaft, means for closing circuit to said motor, and means including a device on said cam shaft and operable to maintain the circuit to said motor closed once the means for closing circuit to said motor has been operated and operable to open circuit to said motor after said rotatable shaft has made a predetermined number of revolutions.

10. In an apparatus for advancing a spring retainer past the adjacent portions of a plurality of spaced apart and aligned sets of springs, a rotatable shaft, a connector on said shaft to which one end of a spring retainer may be secured, a motor for driving said shaft, a cam shaft, means for rotating the cam shaft from the rotatable shaft in predetermined relation with the rotatable shaft, means including a member on said cam shaft for maintaining said motor in operation once said motor has been set in operation and operable to open circuit to said motor after said rotatable shaft has made a predetermined number of revolutions, brake means for decelerating the rotatable shaft and the cam shaft, and means including a part on said cam shaft and operable to render said brake means effective substantially simultaneously with the opening of the circuit to said motor.

11. In an apparatus for advancing a spring retainer past the adjacent portions of a plurality of spaced apart and aligned sets of springs, a rotatable shaft, a connector on said shaft to which one end of a spring retainer may be secured, a motor for driving said shaft, a cam shaft, means for rotating the cam shaft from the rotatable shaft in predetermined relation with the rotatable shaft, means including a member on said cam shaft for maintaining said motor in operation once said motor has been set in operation and operable to open circuit to said motor after said rotatable shaft has made a predetermined number of revolutions, and means including a part on said cam shaft and operable to stop said cam shaft and said rotatable shaft in an identical position each time the circuit to said motor is opened.

12. In an apparatus for advancing a spring retainer past the adjacent portions of a plurality of spaced apart and aligned sets of springs, a rotatable shaft, a connector on said shaft to which one end of a spring retainer may be secured, a motor for driving said shaft, a cam shaft, means for rotating the cam shaft from the rotatable shaft in predetermined relation with the

5 rotatable shaft, means including a member on said cam shaft for maintaining said motor in operation once said motor has been set in operation and operable to open circuit to said 5 motor after said rotatable shaft has made a predetermined number of revolutions, brake means for decelerating the rotatable shaft and the cam shaft, means including a part on said cam shaft and operable to render said brake substantially simultaneously with the opening of the 10 circuit to said motor, means including a part on said cam shaft and operable to stop said cam shaft and said rotatable shaft in an identical position each time the circuit to said motor is opened, and means for supporting the apparatus 10 for movement relative to said sets of springs.

10 13. In an apparatus for advancing a spring retainer past the adjacent portions of a plurality of spaced apart and aligned sets of springs, a rotatable shaft, a connector on said shaft to 15 which one end of a spring retainer may be secured, a motor for driving said shaft, a cam shaft, means for rotating the cam shaft from the rotatable shaft in predetermined relation with the rotatable shaft, means for closing circuit to 20 said motor, means including a device on said cam shaft and operable to maintain the circuit to said motor closed once the means for closing circuit to said motor has been operated and operable to open circuit to said motor after said 25 rotatable shaft has made a predetermined number of revolutions, and means for supporting the apparatus for movement relative to said sets of springs.

14. In an apparatus for advancing a spring 30 retainer past the adjacent portions of a plurality of spaced apart and aligned sets of springs, a rotatable shaft, a connector on said shaft to which one end of a spring retainer may be secured, a motor for driving said shaft, a cam 35 shaft, means for rotating the cam shaft from the rotatable shaft in predetermined relation with the rotatable shaft, means including a member on said cam shaft for maintaining said motor in operation once said motor has been set in operation and operable to open circuit to said motor after said rotatable shaft has made a predeter-

5 mined number of revolutions, brake means for decelerating the rotatable shaft and the cam shaft, means including a part on said cam shaft and operable to render said brake means effective substantially simultaneously with the opening of the 10 circuit to said motor, means including a part on said cam shaft and operable to stop said cam shaft and said rotatable shaft in an identical position each time the circuit to said motor is opened, and means for supporting the apparatus 10 for movement relative to said sets of springs.

15. The method of forming a spring unit or assembly of the character which includes longitudinal and transverse rows of spring coils and in which the spring coils in said transverse rows are 15 mechanically interconnected together in opposing pairs by means of helical retaining elements, which method comprises arranging said spring coils in longitudinal and transverse rows upon a supporting surface and holding them temporarily 20 against movement thereon, mechanically and automatically intermittently rotating a helical retaining element axially a predetermined number of revolutions to effect advance thereof in uniform sequential steps in a direction, parallel 25 to and between said longitudinal rows, and connecting the leading end of said element around one convolution in each of the coils in the two longitudinal rows between which it is advanced to thereby cause the element to wind around said 30 convolutions and thereby tie opposing coils in said transverse rows together in pairs.

16. The method defined in claim 15 in which both the advancing or axial movement and the 35 rotative movement of said helical retaining element are mechanically and automatically stopped after said helical retaining element has been rotated a predetermined number of times and thereby advanced axially during each sequential step or movement thereof, and with the leading end 40 portion of said helical retaining element extending downwardly to thereby facilitate connection of the element about the convolutions to which it is to be connected.

GEORGE E. TAYLOR. 45
